ABSTRACT

Describes a process and apparatus for the electrolysis of HCl containing solutions in unipolar and bipolar cells using graphite electrodes in which the chlorine and hydrogen and the anolyte and catholyte liquor produced in the process are kept separate by means of separate discharge channels in the electrodes with which the active faces of the anodes and cathodes communicate and through which the acid leaves the cells in such a manner as to give longer diaphragm life.

**PROCESS AND APPARATUS FOR THE
ELECTROLYSIS OF HCl CONTAINING
SOLUTIONS WITH GRAPHITE ELECTRODES
WHICH KEEP THE CHLORINE AND HYDROGEN
GASES SEPARATE**

Hydrochloric acid has been electrolyzed on graphite electrodes, to produce chlorine and hydrogen, for many years. Apparatus built proponderantly on the same principles and of the same materials as used from the beginning of this industry, with some enlargements and small improvements has been used; see Ullmann, 3rd Edition, Vol. 5, page 303. The standard capacity unit, today, is a bipolar electrolyzer loaded to 10,000 Amp. with 30 - 50 electrode elements in series, producing in the case of 50 elements approximately 15,000 kg chlorine per day.

The weak point of all prior electrolyzers is the space between the electrodes, especially the diaphragm, which has the duty to keep the two produced gases separate. This diaphragm is a cloth of polyvinyl chloride fibers, which is assembled between the electrodes and held in place by the frames of synthetic material, similar to a drum-skin. See, for example, my prior U.S. Pat. No. 3,236,760.

The supply of HCl is provided by introduction of hydrochloric acid with a concentration of more than 18% HCl, i.e., more than the concentration of the depleted acid, into the cells between the electrodes. This feed acid has not only to substitute the previously electrolytically decomposed HCl, but it takes off also the Joule heat produced in the electrolyzer. Thus, feed acid in the prior art is introduced in two separate streams of HCl on each side of each diaphragm one flows through the anodic room, the other through the cathodic room, losing a fraction of its HCl content, while passing through the cell. The feed rate of the acid is such as to keep the HCl concentration of the depleted acid at approximately 18% by weight, corresponding to the maximum electrical conductivity of the electrolyte.

The purpose of the splitting of the feed acid into two parts is to eliminate as quickly as possible the chlorine gas bubbles in the anode space and the hydrogen gas bubbles in the cathode space, which increase the electric resistance of the electrolyte and the cell voltage. At the usual cell temperature of 70°C about 21 vol.% of water vapor are present in the Cl₂ and H₂ gases.

As long as the diaphragm cloth is not damaged, fairly pure chlorine and hydrogen is produced. The purity is 99.7 - 99.9 vol.% on the dry basis.

Polyvinyl chloride, as compared with other materials, is the more resistant material for the diaphragms. In HCl electrolyzers, however, it undergoes a slow modification by chlorination, which makes the fibers brittle, so that finally they do not have sufficient tensile strength to withstand the conditions of use in a HCl electrolysis cell. Cracks and holes are formed in the cloth and its capacity to keep the gases separate is reduced after a few months to the point where not only the purity of the gases becomes unsatisfactory, but the danger of explosion of the formed mixtures of Cl₂ and H₂ is increased. In order to eliminate this danger, it is necessary to stop the electrolyzer and to replace the damaged diaphragms by new PVC diaphragms. Fluttering and flexing of the diaphragms caused partially by the introduction of the HCl feed on each side of the diaphragms contributes to their rapid destruction.

The present invention as described in the following examples largely overcomes this defect.

One of the basic principles of the apparatus and process of the present invention is to avoid the self-supporting diaphragm as used previously, which when submitted to the action of strong mechanical forces in the prior art cells, produced fluttering, a phenomena which not only includes the high power peaks of the fluttering, but also causes the continuous bending of the fibers as they become more and more brittle and leads to rapid destruction of the diaphragms.

One of the principal objects of this invention is the substitution of the two feed acid streams used in the prior art, by a single feed stream which pushes the diaphragms which are pervious to the gases and electrolyte against the solid supports of the anode or cathode faces, thereby reducing bending and fluttering of the diaphragms. I have found that the diaphragms can be protected from the mechanical stresses if they are supported as fully as possible on the more or less solid grids of the anode and cathode faces. This results in a longer life for the diaphragm or diaphragms. In addition, the diaphragms according to the present invention may be supported on rigid grids or networks made of resistant material, such as Teflon, Plexiglass and so on. Such a grid increases the electrode gap and the ohmic resistance of the cell by a slight amount, but prolongs the life of the diaphragms.

Another object of the invention is to support the diaphragm or diaphragms on a rectangular parallelepiped of graphite, provided with blades and slots, used as the electrodes, i.e., anodes and cathodes, provided at regular intervals with bore holes or channels approximately 20 - 40 mm in diameter, parallel to the large surface planes of the electrodes and preferably parallel to their shorter rectangular dimension, which bore holes conduct the produced gases and depleted electrolyte away from the electrode surfaces and eventually out of the cell. The inside surfaces of the said bore holes are painted with a suitable liquid, for instance, with a cold curing phenolic resin, in order to avoid erosion of the soft graphite by the moving gases and liquids during the operation of the cell. This simple resin painting is very useful, because it allows the use of a lower graphite quality while still providing adequate discharge channels for the discharge of the formed gases and of the spent electrolyte, a portion of which may be recirculated as later described.

In order to keep the surfaces of the graphite blades electrically active, the resin painting, including hardening of the resin layer, should be done after drilling of the bore holes, but before cutting the slots on the surfaces of the graphite electrodes.

After the hardening of the resin, a set of saw discs on a common axle is used to cut a multiple of parallel slots on the surfaces of the graphite plates provided as electrodes, the direction of the parallel slots with reference to the bore holes preferably being an angle of approximately 90°, although this angle may vary substantially from 90°. The slots are of such a depth that they penetrate a few millimeters into the cavities of the bore holes where they cross the bore holes, creating in this way a connection between the bore holes and the cavities of the slots. The slots should have a width of approximately 1 - 2 mm and a depth of 5 - 20 mm, while the graphic blades between the slots should have a thickness of approximately 1 - 3 mm. During electroly-

sis, the graphite blades are the electrodes (i.e., anodes and cathodes), while the slots receive the two produced gases and discharge them into the corresponding bore holes. The bore holes and the slots in the graphite electrodes may be produced by other methods.

Referring now to the drawings which show preferred forms of embodiment of the invention and some, but not all, of the possible modifications thereof, and are intended only as illustrative embodiments.

FIG. 1 is a schematic illustration of a unipolar graphite electrode used as a terminal electrode at either end of a bipolar HCl cell assembly;

FIG. 2 shows a similar unipolar graphite electrode with additional slots at right angles to the slots shown in FIG. 1;

FIGS. 3 and 3a are, respectively, a face view and a side view of the graphite plates which form the bipolar electrodes of an assembled cell;

FIG. 4 is a plan view of the bipolar electrode shown in FIG. 3;

FIG. 5 is a cross sectional plan view of a bipolar electrode showing the bore holes provided with guide sheets, to permit release of gas and provide downward recirculation of a portion of the electrolyte;

FIGS. 6, 7, 8, 9 and 10 show modified forms of slots and bore holes in diagrammatic plan views;

FIG. 11 is a vertical sectional view through a bipolar electrode along the line 11 — 11 of FIG. 13;

FIG. 12 is a vertical section along the line 12 — 12 of FIG. 11;

FIG. 13 is a horizontal section in diagrammatical outline, of an assembled cell along the line 13 — 13 of FIG. 11;

FIG. 14 is a detail of one form of electrolyte feed and FIG. 14a shows another form of electrolyte feed, using Venetian blinds instead of sheet diaphragms;

FIGS. 15, 16 and 16a are, respectively, a detail, a face view and a side view of a Plexiglass or Teflon frame for holding the diaphragms against the electrode faces;

FIG. 17 is a sectional view along the line 17 — 17 of FIG. 13;

FIG. 18 is a schematic end view of the electrolyzer shown in FIG. 13, this view being substantially the same from either end of the electrolyzer;

FIG. 19 is a vertical section along the line 19 — 19 of FIG. 20, parallel to the direction of the slots and graphite blades, showing the electrodes in horizontal position and showing diaphragms on only one face of the cathodes;

FIG. 20 is a horizontal section along the line 20 — 20 of FIG. 19;

FIG. 21 shows an enlarged vertical section through a slightly different form of electrode package, showing diaphragms in dash lines along both the anodic and cathodic faces of the bipolar electrodes;

FIG. 21a is a cross sectional detail of FIG. 21;

FIG. 22 shows an enlarged view of the top part of a bipolar electrode in horizontal position with the diaphragm omitted;

FIG. 23 is a horizontal section along the line 23 — 23 of FIG. 19;

FIG. 24 is a view of a sight glass arrangement along the line 24 — 24 of FIG. 23, for checking the electrolyte level in single cells; and

FIG. 25 shows an example of a bipolar electrolyzer with the electrode faces in horizontal position.

The unipolar graphite electrode shown schematically in FIGS. 1 and 2, comprises a graphite slab 1 having bore holes 2 for discharging the gas and depleted electrolyte and horizontal slots 3 separated by blades 4.

5 The slots 3 are preferably about 1 to 2 mm wide and about 5 to 20 mm deep and intersect the bore holes 2, so that gases produced on the electrode and depleted electrolyte flowing into the slots will go into the resin lined bore holes 2 and be discharged at the top of the

10 electrode. The first bore hole in FIG. 1 has been cut away to show the communication between the slots 3 and the bore holes 2. Vertical slots 3a shown in FIG. 2, may be provided to increase the surface area of the blades 4. The slots 3 and 3a need not be at 90° one to

15 the other. The slots 3a may be at any desired angle to the slots 3, such as 5° to 90°. The blades 4 are preferably about 1 to 3 mm thick.

The electrodes 1 shown in FIGS. 1 and 2, may constitute the positive and negative electrodes of a single cell, 20 or the terminal positive and the terminal negative electrode of a bipolar electrolyzer which may, for example, have forty or more bipolar intermediate electrodes such as shown in FIGS. 3 and 4.

The slots may be formed in the graphite slab 1 in any 25 suitable manner, as by spaced circular saw blades on a common axis, or by building the electrode from individual plates of graphite having holes 2 and having the slots and blades given above therein. The plates are stacked one on top of the other, with the smaller plates 30 between the larger ones and then cemented together to form electrodes of the construction shown in FIGS. 1 and 2.

In use, the electrodes of FIGS. 1, 2 and 3 may be covered with diaphragms which rest on the crest of the 35 graphite blades 4. In FIGS. 1 and 2, the diaphragms have been omitted to give greater clarity to these figures. The direction of the slots 3 and the bore holes 2 need not be, respectively, horizontal and vertical or at 40 90° each to the other. The slots 3 can, for example, be vertical and the resin lined bore holes 2 horizontal, preferably with a slight upward tilt toward the discharge end of the electrolyzer as will be described hereafter. The crest of the blades 4 may have shallow slots, about 0.1 to 1 mm, cut into the graphite surface before the deeper slots 3 are cut, to give the crest of the blades 45 additional roughness.

FIGS. 3, 3a and 4 illustrate a bipolar electrode 5 suitable for use as an intermediate electrode in a multiple 50 unit bipolar electrolyzer. The front and back faces of the electrode of FIG. 3 are provided with slots 3 and blades 4, as the FIGS. 1 and 2, and the slots 3, shown in dash lines in FIG. 4, communicate with independent sets of bore holes 2 and 2a in the graphite slabs to discharge gases and electrolyte from the anodic and cathodic faces of the electrode through the bore holes.

Further alternative forms of bipolar electrodes are shown schematically in FIGS. 6, 7, 8, 9 and 10, in which the slots 3, shown in dash lines, are in garland or wave form communicating with the bore holes 2 and 60 2a, one of which discharges Cl₂ and depleted HCl acid through the bore holes 2 from the anodic side of the electrodes, and the other holes 2a discharge H₂ and depleted acid from the cathodic side of these bipolar electrodes, as shown in FIGS. 8, 9 and 10. The wave or garland form of the slots 3 may be produced by circular saw blades moving in and out of graphite slabs 1, or this form of electrode may be produced by alternate layers 65

of thin plates having the wave shape illustrated and rectangular plates forming the blades 4, stacked one on top of the other to the height desired and cemented together. Other methods of forming the alternate slots 3 and blades 4 may be used. In any form of construction, the bore holes 2 and 2a are coated on the inside with a suitable coating such as a cold curing phenolic resin, to reduce erosion of the bore holes by the gases and liquids moving therethrough during operation of the cell.

The bore holes 2 and 2a may be arranged in a single plane as illustrated in FIG. 7 or in a zigzag pattern as illustrated in FIGS. 4 and 6. When the bore holes 2 or 2a are located beyond the center of the electrode, with reference to the anodic face, the average depth of the anodic slots may be made bigger than the slots on the cathodic side of the electrodes, to provide a larger wear dimension of the anodic graphite blades. This form is shown in FIG. 10. Various combinations of slots and bore holes may be made. The slots may be formed by sawing the graphite slabs 1, by assembling and cementing together the stacked layers of slotted plates and rectangular plates or in other ways and the bore holes 2 may be formed by drilling (before the formation of the slots) or by cementing together graphite sections formed by extrusion, block pressing machining or the like, to provide bore holes 2 and 2a in the graphite sections 1a of FIG. 6.

In use, the bore holes 2 and 2a when in vertical or nearly vertical position, are more or less flooded with electrolyte and in order to facilitate quick release of the gases and downward recirculation of the electrolyte, the bore holes may be subdivided by guide vanes 6 of Teflon, Plexiglass or the like, preferably into two unequal parts as illustrated in FIG. 5, so that the gas bubbles rise, together with the electrolyte in the larger section of the bore holes, while the smaller section allows downward recirculation of the electrolyte. A similar result may be secured by providing larger bore holes in the graphite electrodes and parallel smaller holes which communicate with the larger bore holes only near the top and bottom of the electrodes, so that the gas bubbles and electrolyte will rise in the larger bore holes and when the gas bubbles are released at the top of the bore holes the smaller bore holes will provide passage for the downward recirculation of the electrolyte, freed from the gas bubbles.

FIG. 13 is a horizontal sectional plan view along the line 13 — 13 of FIG. 11, showing an electrolyzer with a number of bipolar electrodes, the negative and the positive terminal electrodes and the gas collector domes 7 and 7a for Cl₂ and H₂, respectively. For clearness, gaps have been left between the electrode components 8, 9, 10, 11 and 12 of the electrolyzer where spacing gaskets are used and the slotted electrode faces 15 and comb-like feed frames 14 (see FIG. 14) for the feed acid are omitted. The slotted electrode faces 15 are in direct contact with diaphragms 13 which have an appropriate permeability for liquid and current; the diaphragms may be deposited polyvinyl chloride or be prefabricated.

Deposited diaphragms may contain loose PVC fibers with the addition, if desired, of other types of fibers, even chemically less resistant, such as asbestos, rayon, cotton, etc., with minor quantities of binders which may be added as liquids, pastes, emulsions, etc.

Prefabricated diaphragms may have the character of fleeces, containing PVC fibers or other resistant fibers, added asbestos fibers, rayon fibers, cotton and other less resistant fibers as well as colloid binders introduced, for example, by impregnation of the fiber fleece with a diluted alcoholic solution of phenolic resin, a solution of alkali silicate or alkali cellulose Xanthogenate or with mixtures of the two latter solutions or of other materials and subsequent treatment with acids, heat, etc.

Other types of prefabricated diaphragms are cloths, such as PVC cloths, impregnated with chemical agents, as above mentioned, in order to give to the diaphragms the correct permeability for the electrolyte. In order to maintain the optimum distance between the cathodic and anodic diaphragms of about 6 to 10 mm, chemically resistant gaskets 14 of this thickness are provided between the flanges of the Haveg frames 16 through surrounding channels 17 in the frames 16 (see FIG. 14). The space between the diaphragms 13 is filled with electrolyte and is the space where the feed acid is fed in.

Deposited diaphragms as well as prefabricated diaphragms can be formed with spray guns as, for instance, in the case of glass fiber reinforced polymers.

The introduction of the feed acid into the diaphragm interspace is done from side walls or bottom walls of the periphery of the Haveg frames 16, according to the dimension of the cell. As shown in FIG. 11, the feed acid from the horizontal feed acid channels 18 — 18 located in the side walls of the elements frames is distributed among all elements 8, 9, 10, 11, 12, etc., of the electrolyzer and through the channels 18a, 18b and 18c of each element frames 16 (see FIG. 11). The feed acid starting from these channels 18 — 18a, etc. flows into the inner part of the comb-like Plexiglass frames, situated between the gaskets 14 and the space between the diaphragm of a single electrolytic cell, as illustrated by the arrows in FIG. 14.

The thin comb-like Plexiglass frame 14 shown in FIGS. 16 and 16a and in an enlarged detail in FIG. 15, is held fast between the Haveg frame 16 as shown in FIG. 14 all around the frame flanges 16; it is comb-like only on the sides and bottom, while the upper portion of the Plexiglass frame 14 has rectangular holes for the passage of Cl₂, H₂ and depleted acid flowing to the Cl₂ and H₂ manifolds 7 and 7a. The Plexiglass frames are held in position between gaskets all around the cell frames 16 and the gaskets transmit the pressure also to the rims of the two diaphragms holding them in position. In FIG. 14, the two diaphragms 13 are indicated as dash lines on the crests of the graphite blades 4; they extend to the neighborhood of the final Cl₂ and H₂ distribution channels at the top of the Haveg frames 16.

FIG. 14 shows as a vertical section the lowest parts of vertical bore holes 2a for H₂. In each bore hole, the lower end of the guide sheet 6 can be seen around which the electrolyte stream, coming downwards in the smaller part of the bore hole cross section, changes its direction and starts rising again in the larger cross section part of the bore holes, taking with it new H₂ bubbles and new electrolyte introduced through diaphragms and graphite slots. When this electrolyte stream arrives at the upper end of the bore holes 2a, the bulk of the H₂ bubbles and the part of electrolyte which

corresponds to the feed rate is discharged into the horizontal H_2 collector channels of the Haveg frames. See FIGS. 11 and 13. The same construction is used for the Cl_2 bore holes.

The assembled electrolyzer such as illustrated diagrammatically in FIG. 13, consists of a terminal positive electrode 8, a terminal negative electrode 12 and any desired number, for example, forty intermediate bipolar electrodes 9, 10, 11, etc. Each electrode is provided with slots 3 and blades 4 and with bore holes 2 and 2a, as illustrated in FIGS. 1 to 5. The terminal and intermediate electrodes are assembled between stiffened head pieces 21 and 22 which are rubber lined on the inside and are provided toward the top thereof with collecting chambers 7 and 7a for Cl_2 and H_2 . The head pieces 21 and 22 are similar and as illustrated in FIG. 18 have graphite rods 23 for connecting the electrolyzer into an electric circuit. The head pieces 21 and 22 are connected by several long bolts 24, suitably insulated, which hold the head pieces and the electrodes 8, 9, 10, 11, 12, etc. together. The electrolyzer is mounted on a suitable insulated steel frame.

Each electrode 8, 9, 10, 11, 12, etc. is surrounded by a Haveg or other suitable frame 16 which has channels 17 through which the feed acid is fed into the space between the diaphragms 13 resting on the slotted electrolyzer faces 15 (see FIG. 14). The Cl_2 gas and electrolyte rising through the bore holes 2 flows horizontally through the conductor channels 25 to the Cl_2 collector chamber 7 where the Cl_2 is separated from the depleted electrolyte and flows to the Cl_2 collector system while the depleted electrolyte flows downward to a resaturator and is recycled to the electrolyzer. The H_2 and depleted electrolyte rising in the bore holes 2a flows to the collector chamber 7a the gas and electrolyte is separated and recovered in a similar manner. FIGS. 17 and 18 illustrate this gas and electrolyte separation and recovery system. The diaphragms, gaskets and other parts are omitted from FIGS. 13, 14 and 17 for greater clarity.

FIG. 11 shows a vertical section along the line 11 — 11 of FIG. 13 through a bipolar electrode. The Haveg frame 16 contains on its upper end a number of cavities 20 and 25 which form, after the assembly, with other frames the horizontal discharge channels for Cl_2 and anodic depleted electrolyte and for H_2 and cathodic depleted electrolyte. Each one of the horizontal parts of the channels for Cl_2 of a frame is connected with the upper end of a coordinated vertical bore hole 2 for Cl_2 and anodic depleted electrolyte, each one of the horizontal parts of the channels for H_2 of a frame is connected with the upper end of a coordinated vertical bore hole 2a for H_2 and cathodic depleted electrolyte and discharges its H_2 gas and its depleted acid into the horizontal channel, which guides both into the collector dome 7a for H_2 , situated on one end of the electrolyzer and on the other end of the electrolyzer there is a similar collector dome 7 for Cl_2 gas and for the depleted anodic electrolyte to be discharged from the electrolyzer. FIG. 12 is a vertical section of a bipolar intermediate electrode along the line 12 — 12 of FIG. 11.

The electrolyzer illustrated in FIGS. 1 to 18 contains, for example:

(a) a number of bipolar electrodes (for instance, 40) in vertical position; (b) a positive unipolar terminal electrode in vertical position with graphite rods for the

positive current connection; (c) a negative unipolar terminal electrode in vertical position with graphite rods for the negative current connection; (d) a stiffened head piece of steel on the anodic end of the electrolyzer rubber-lined or insulation on its inside and containing also the collecting domes for chlorine gas and the anodic depleted electrolyte; (e) a stiffened head piece of rubber-lined steel on the cathodic end of the electrolyzer containing the collecting dome for hydrogen gas and the cathodic depleted electrolyte; (f) the long bolts, pressing the package of elements together; (g) rubber lined horizontal steel beams mounted on insulating concrete bases, on which the cell elements rest; (h) the piping for the feed acid and the feed valve with a flowmeter; (i) the discharge pipes for chlorine, hydrogen and for the cathodic and anodic depleted acids; (k) a short circuit switch for the interruption of the current in the electrolyzer whenever necessary.

20 Each bipolar electrode 5 is composed of a graphite electrode with two electrolytically active faces. Each of the active electrode faces is maintained and has graphite blades 4 about 2 mm thick with slots 3 about 1 — 2 mm wide and about 5 to 20 mm deep between the blades. The planes of the blades and the slots are preferably horizontal and form with the vertical an angle of, preferably, 90°. A Haveg frame encircles each graphite electrode and is sealed to the periphery of the graphite electrode by cement which is tight against liquid and gas.

25 FIG. 14a shows a modification in which Venetian blind deflectors 13a are used in place of the diaphragms 13 of FIG. 14. The Venetian blind deflectors 13a may be formed of Teflon, PVC or any other material which is resistant to the electrolyzer conditions and are mounted close against and touching the anodic and cathodic electrode faces 15 and tilted upwardly so as to deflect gas and electrolyte rising between the electrode faces into the slots 3 and, hence, into the bore holes 2. The gap between the anodic and cathodic graphite faces in this instance must be a little wider than where flat diaphragms are used, preferably, about 5 to 8 mm. Venetian blinds 13a and diaphragms 13 may be used together, if desired.

30 40 45 An excess flow of feed acid through the electrolyzer is needed for the elimination of the heat produced in the electrolysis. The cooling power of the system is controlled by the amount of feed acid circulated per hour, and the difference between the desired optimal electrolyzer temperature and the temperature of the entering cooling medium feed acid, which is a mixture, for instance, of concentrated 33% HCl recycled depleted acid with about 18% HCl. The recycled depleted acid is cooled, so that the cooling power corresponds to

$$(t^o_{cell} - t^o_{feed\ acid}) \times X \text{ kg feed acid/hour}$$

50 55 at constant cell current and remains practically unchanged (if an eventual slight change of the cell voltage is not taken in consideration) in cells with diaphragms. The introduction of the feed acid into the space between the two diaphragms or the two Venetian blinds is accomplished best in the horizontal direction, starting from the two sides of the Haveg frames. The slight increase of the length of the current path from the anode to the cathod in cells equipped with Venetian blinds is (in view of the cell voltage) about compen-

sated for by the elimination of the diaphragms with their unavoidable voltage drop. The guide sheets of plastic material in the vertical bore hole or in the case of secondary down comer bore holes can be omitted, with the Venetian blinds, because the increased amount of feed acid introduced for the rapid gas release through the bore holes provides sufficient upward transport speed for the gas H_2 and Cl_2 gas bubbles through the bore holes of the electrodes. Cells with Venetian blinds have the advantage of a longer operation time between repairs.

Instead of a full substitution of the diaphragms by Venetian blinds, diaphragms may be used with Venetian blinds, with the following advantages:

1. The feed rate of acid into a cell can be lower compared with the use of Venetian blinds only;
2. The diaphragms used in such a combination can be of a lower ohmic resistance, without reducing the gas purity;
3. Even at the end of the diaphragm lifetime, the danger from explosive gas mixtures is low and the interruption of the cell operation for diaphragm renewal is still less urgent when Venetian blinds are used than in the case of diaphragms alone; and
4. The combination of Venetian blinds with diaphragms is especially favorable on the anodes.

In both cases of cells with vertical position of the electrodes, the spaces between electrodes (respectively diaphragms) must be kept flooded with electrolyte as long as the cells are in operation, in order to avoid mixture of gases. Indicator tubes, provided between the diaphragms on the upper end of each of the element frames, must always show a visible electrolyte level.

These indicator tubes, well known in the industry and shown with the horizontally positioned electrodes of FIGS. 23 and 24, have a second function, namely, as outlet for small quantities of gas which might have passed from one of the two electrode rooms into the space between the diaphragms and which would otherwise accumulate in the upper part of this space. Such small gas quantities eventually discharged from the interdiaphragm space are collected under their own pressure in a waste gas pipe and piped out of the cell room. These indicator tubes are used with both horizontally and vertically positioned electrodes.

If an electrolyzer with vertical electrodes such as illustrated in FIGS. 1 to 18, is to be emptied and if a renewal of the diaphragms is not intended, care has to be taken that the electrolyte (or also wash water) is discharged contemporaneously from all the electrode rooms, but not from the interspace between the diaphragms. This precaution is not needed in the case of Venetian blinds only.

Another electrolyzer type, illustrated in FIGS. 19 to 24, based on the above-mentioned inventive principles, has electrodes and diaphragms in horizontal position, as described below.

As a consequence of the horizontal electrode position, the gas bubbles produced on the upper electrode, for instance, on the anode, remain by their buoyancy in the electrolyte separated from the gas produced on the lower electrode, in this case on the cathode. However, it is necessary to use a diaphragm covering the lower electrode, to prevent the gas of the lower electrode from rising up. This diaphragm must be continuously covered with a layer of electrolyte. The structure of the electrodes is the same as in the vertical electrode

embodiment previously described. The bore holes for the gases and for the depleted electrolyte are in horizontal position, the slots and the graphite blades of the electrode surfaces are also horizontal and offset relative to the axes of the bore holes.

The introduction of the feed acid into each cell is made continuously into the space between the diaphragms, if both electrodes are covered with a diaphragm, if not, into the space between the upper electrode and the diaphragm which covers the lower electrode of the cell. The introduced acid flows partially through the diaphragm of the lower electrode, through its slots into the corresponding bore holes and leaves the cell together with the there produced gas. The other part of the feed acid flows through the upper diaphragm (if any) of the cell and passes together with the gas produced on the upper electrode through its slots into the corresponding bore holes and leaves the latter by outflow on one end of these bore holes, flowing into the vertical collector channels for Cl_2 and H_2 . In contrast to cells with vertical electrodes, the bore holes of the cells with horizontal electrodes are not flooded, but are mainly full of gas. FIGS. 19 to 24 illustrate an embodiment of this invention in which the electrodes are in horizontal position.

FIG. 19 shows a vertical section along the line 19 — 19 of FIG. 20, through a part of an electrode package parallel to the direction of the slots and the graphite blades 4 on the surface of the electrodes. Within one cell, the lower electrode 26 is the cathode; it is covered with a diaphragm 13 shown in dash lines, which may be a slurry deposited or a prefabricated diaphragm. On the right side of FIG. 19 parts of the sides 16 of the Haveg frames are shown; on the thicker parts of the Haveg frame the vertical common acid feed duct 27 for the feed acid is provided. The acid feeds through the gauged holes 27a into the distributor channel 27b and through the gauged holes 27c into the space between the lower electrode (cathode) and the upper electrode (anode).

FIG. 20 is a horizontal section along the line 20 — 20 of FIG. 19, viewed from below. It shows how a corresponding feed acid fraction under pressure from the vertical main feed duct 27 of the electrolyzer is fed through a gauged hole 27a into the horizontal distribution channel 27b of each element. From here, the feed acid distributes itself approximately equally by passage through a number of small holes or nicks 27c in the frame over one side of each electrode element.

FIGS. 21 and 21a show in substantially natural size, a vertical section through an electrode package. In contrast to FIG. 19, both electrode surfaces of each cell are covered with a diaphragm 13 and the feed acid distribution is accomplished by a thin comb-like frame 14 of plastic material having slots 14a therein, similar to those shown in FIGS. 15 and 16 for vertical electrodes. A small part of this comb-like frame is shown in FIG. 21a.

The profile of the cut slots of the graphite electrodes is the same as shown in FIG. 7. The section of FIG. 21a is made at the position of a slot. The distance between graphite plates and Haveg frames, which can be seen in FIG. 21, is filled with Haveg cement during the assembly.

FIG. 22 shows in approximately natural size, the top view of a part of a bipolar plate of FIGS. 19, 20 and 21. The diaphragm is omitted and so the partially designed

cathodic graphite blades 4 and slots 3 and the vertical collector channels 28 for the chlorine gas in the Haveg frame 16 can be seen. The similar collector channels 28a for the hydrogen gas are situated on the opposite side of the frame (See FIG. 23). The bore holes 2 and 2a for H₂ and Cl₂ inside the graphite plates as well as a part of the feed acid distributor channel 27b in the frame with a few small holes 27c between this channel and the cell interior are shown in dash lines.

FIG. 23 is the horizontal section 23 — 23 through FIG. 19. It shows, for example, the total system of feed acid distribution 27, 27a, 27b and 27c for a single element. The feed acid is introduced into the vertical distribution channel 27 from outside, preferably, at half the electrolyzer height or, in the case of a larger number of elements in an electrolyzer, at several places, preferably, one for each of, for instance, 15 to 20 elements.

For large elements, it may be desirable to provide two similar feed arrangements for feed acid introduction on opposite sides of each element frame. FIGS. 23 shows, by dash lines, the gas and electrolyte bore holes 2 and 2a for Cl₂ and H₂. These horizontal bore holes are closed on one end and on the other end open into vertical Cl₂ channels 28 in the Haveg frames. The H₂ bore holes have similar vertical collector channels 28a on the opposite side of the Haveg frames. The gas plus depleted acid is collected on the lower end of the electrolyzer pile and taken by the collector channels 28 and 28a to the outside of the electrolyzer, where the liquid is separated from the gas. The other, preferred, possibility is to discharge the depleted acid from the lower ends of the vertical channels 28 and 28a and to discharge the gases from the upper ends into gas collector chambers, similar to collector chambers 7 and 7a shown in FIG. 13. In the case of electrolyzers with the horizontal electrodes of FIGS. 19 to 23, the thin comb-like distributor frames 14 made of plastic material provided for electrolyzers with vertical electrodes and shown in FIGS. 14, 15 and 16, may be used instead of the above described small holes or nicks 14a, as shown in FIG. 21a.

The preferred positions of anodes and cathodes in a horizontal electrolyzer cell is to have the diaphragm covered cathode at the bottom and the anode with or without diaphragm at the top. In a bipolar graphite electrode plate, the diaphragm covered cathodic face of the electrode plate looks upwards, the anodic face with or without diaphragm looks downwards. It is, however, quite possible to invert these positions. In such an inverted position, the electrode (anode) at the bottom of the cell is covered with a diaphragm, while the electrode at the top (cathode) may or may not be covered with a diaphragm. Also, in the preferred normal position, a diaphragm may cover only the upwards looking cathode or an additional diaphragm may also cover the downwards looking anode. All these modifications are included in the present invention.

The electrolyte levels in the single cells of an electrolyzer can be checked from the outside of the electrolyzer by sight glasses shown, for example, in FIG. 23 as a horizontal section, and as a vertical section in FIG. 24. Each cell of an electrolyzer has on the flange of its Haveg frame, opposite the acid feed side, a channel 29 with connecting holes to the interior of the corresponding cell, lower than the electrolyte level to be checked. Each of these channels is connected by a flexible tube

29a with small transparent indicator pipe 29b, which are inside a larger transparent container pipe 29c. This transparent container pipe 29c is connected by a pipeline with one of the vertical Cl₂ collector channels of the electrolyzer, in order to substitute the pressure of the atmosphere by the pressure of the Cl₂ gas. It is useful to provide a few tap points in different positions, in order to eliminate the disturbing influence of the dynamic pressure drop in the Cl₂ channels. The measured 10 levels in the level indicator pipes 29b of the check container are used to regulate the acid feed and for the detection of any defects of single diaphragms and for the timing of the end of the life of the diaphragms.

FIG. 25 shows by way of example a bipolar electrolyzer with a number of elements 30, the electrode faces being in horizontal position. The Cl₂ and H₂ gases are collected inside chlorine and acid proof lined collector domes of the steel cover 31 and sent to the Cl₂ and H₂ collector systems. The anodic and the cathodic 15 depleted acids are collected on the steel bottom, also lined with chemically resistant material, and discharged to the outside. In the example of FIG. 25, the feed acid is introduced through lines 32 and 32a having two valves, each with a flowmeter, into the two cell groups 20 with eight cells each. The feed acid flow rate can be checked by the checking devices, shown in FIG. 24.

FIG. 25 shows for simplicity only two long bolt 24, however, more are used. Depending on the size of an electrolyzer, four to eight supports with insulators are 25 provided, which are not shown in FIG. 25.

This invention is not limited to the described examples, but may be used in modified forms.

It provides the diaphragms with a longer lifetime by 35 supporting them on the solid electrode faces where they are not subject to flexure or fluttering. The use of the slots 3, blades 4 (and bore holes 2 and the cavity systems inside the electrodes) as support for the diaphragms on a solid base, keeps one or both produced gases away from the electrode gap. The inverted cavity 40 systems concentrating the gases (originally distributed over the whole electrode surfaces) into the bore holes 2 and 2a, each of which acts as collector for the gas from the corresponding surface and being connected with its corresponding gas collector, provides perfect 45 separation of the Cl₂ and H₂ gases.

By feeding the electrolyte into the space between the diaphragms supported on the electrode faces, fluttering and deflection of the diaphragms is reduced or eliminated 50 and provides much longer life for the diaphragms. The extended diaphragm life results in saving of labor for the renewal of the diaphragms, reduces loss of production and avoids the formation of explosive mixtures of Cl₂ and H₂.

The energy saving, resulting from the practically gas 55 bubble free electrode gap results in a reduction of the cell voltage by about 0.1 to 0.15 volt.

There is an appreciable saving in floor space in the case of horizontal electrodes, because these apparatus 60 (FIG. 25) are towers, which are able to operate in the open air and permit especially economic construction.

By feeding the acid into the space between the two 65 electrode supported diaphragms, contamination of the produced gases is virtually impossible in all stages of diaphragm age and a higher gas purity is assured.

It will be obvious to persons skilled in the art that many modifications and changes may be made from the

specific embodiments shown without departing from the spirit and scope of the inventions described.

I claim:

1. In a hydrochloric acid electrolyzer, means to feed acid to be electrolyzed to said electrolyzer, means to conduct electrolyzing current to said electrolyzer, spaced graphite electrodes in said electrolyzer, slots and blades on the faces of said electrodes, two separated sets of bore holes in the interior of each of said electrodes, connections between the slots and one set of bore holes by which hydrogen produced on one face of the electrodes and depleted acid are conveyed to one set of bore holes and connections between the slots and another set of bore holes by which chlorine produced on another face of the electrodes and depleted acid are conveyed to another set of bore holes and means to conduct hydrogen and depleted acid from one set of bore holes and chlorine and depleted acid from another set of bore holes to the outside of the electrolyzer.

2. In the electrolyzer of claim 1, a diaphragm supported against a face of each electrode.

3. The electrolyzer of claim 2, in which the diaphragms are polyvinyl chloride.

4. In the electrolyzer of claim 2, a plurality of bipolar electrodes, means to space the electrodes apart, diaphragms supported against each face of each electrode, means to feed acid to be electrolyzed into the electrolyzer between the diaphragms and means to discharge gases and depleted acid from the electrolyzer through said bore holes.

5. The electrolyzer of claim 1, having rows of slots on the face of the electrode intersecting each other at angles of from 5° to 90° to each other.

6. The electrolyzer of claim 4, having a plurality of bipolar electrodes mounted between head pieces and held together between the head pieces by long bolts, a gas and liquid collector chamber in each head piece, two sets of bore holes in each electrode and channels for gas and liquid connecting each set of bore holes with one of said gas and liquid collector chambers.

7. The electrolyzer of claim 6, in which a plurality of bipolar electrodes are mounted between unipolar terminal positive and negative electrodes and all the said electrodes are mounted between the said head pieces and the head pieces are provided with connector rods for connecting the terminal electrodes into the electrical circuit.

8. The electrolyzer of claim 6, having means in each gas and liquid collector chamber to separate the gas from the liquid.

9. The electrolyzer of claim 1, having a plurality of electrodes, means to space the electrodes apart, venetian deflectors supported against the face of each electrode and means to feed acid to be electrolyzed to the electrolyzer between venetian deflectors.

10. The electrolyzer of claim 9, having both venetian deflectors and diaphragms supported against the elec-

trode faces.

11. The electrolyzer of claim 1, in which the slots between the blades are in garland like waves communicating with said bore holes.

5 12. The electrolyzer of claim 1, in which the blades have a width of about 1.5 to 3 mm, the slots have a width of about 1 to 2 mm and are about 5 to 20 mm deep and the bore holes are about 20 to 40 mm wide and intersect the slots.

10 13. The electrolyzed claim 1, in which the electrodes are arranged in vertical planes.

14. The electrolyzer of claim 1, in which the electrodes are arranged in horizontal planes one above the other and at least one diaphragm rests against the 15 upper face of the lower electrodes.

15. The electrolyzer of claim 1, in which partitioning inserts inside the bore holes divide the bore holes into two unequal passages.

20 16. The method of providing recirculation of depleted acid in a hydrochloric acid electrolyzer according to claim 1 having electrodes with substantially vertical bore holes for discharge of gases and depleted acid from the faces of the electrodes which comprises providing recirculation channels within the electrodes and recirculating the depleted acid rising with the gases in said bore holes downward through said recirculation channels after the gases have been discharged from the depleted acid toward the top of the said bore holes.

25 17. The method of claim 16 in which the bore holes are provided with partitions and the gases and depleted acid are circulated upwardly on one side of said partitions and the depleted acid free from the gases is recirculated downwardly on the other side of said partitions.

30 35 18. In a hydrochloric acid electrolyzer, a plurality of bipolar graphite electrodes, each having parallel slots and blades on the front and back face thereof, two separated sets of bore holes in each of said electrodes with which the slots communicate, a diaphragm resting against the blades of each electrode face, means to space the electrodes and diaphragms apart, means to feed acid electrolyte to be electrolyzed into the spaces between the electrodes and diaphragms, means to maintain a hydrostatic pressure differential between the side of each diaphragm facing the feed acid inlet space and the side of the diaphragms resting against the blades of the electrodes and means to convey hydrogen and depleted acid into one set of bore holes and means to convey chlorine and depleted acid into another set of bore holes and means to separately discharge hydrogen and depleted acid from one set of bore holes, means to separately discharge chlorine and depleted acid from another set of bore holes and means to separately discharge said hydrogen and depleted acid and said chlorine and depleted acid from said electrolyzer through said bore holes.

UNITED STATES PATENT OFFICE
CERTIFICATE OF CORRECTION

Patent No. 3,855,104

Dated December 17, 1974

Inventor(s) Georg Messner

It is certified that error appears in the above-identified patent and that said Letters Patent are hereby corrected as shown below:

- Col. 2, line 55, "rein" should be -- resin --
- Col. 7, line 35, after "7a", insert -- and --
- Col. 8, line 8, "stiffened" should be -- stiffened --
- line 22, "maintained" should be -- machined --
- line 52, after "HCl", insert -- containing new acid and of --
- Col. 10, line 23, the sentence beginning "Figs. 19 to 24" should start a new paragraph

Signed and sealed this 29th day of April 1975.
